Atty.

UNITED STATES PATENT OFFICE.

CLARENCE F. LYNN, OF CANANDAIGUA, NEW YORK.

AUTOMOBILE DIRECTION-SIGNAL.

1,391,686.

Specification of Letters Patent. Patented Sept. 27, 1921.

Application filed March 12, 1921. Serial No. 451,684.

To all whom it may concern:

Be it known that I, CLARENCE F. LYNN, a citizen of the United States, residing at Canandaigua, in the county of Ontario and 5 State of New York, have invented certain new and useful Improvements in Automobile Direction-Signals, of which the following is a specification.

My invention relates to direction signals 10 for automobiles.

The object of the invention is to provide a simple and efficient direction signal in which a single inclining rotary shaft with an illuminated triangular hollow tapered 15 pointer set at an angle at the outer end thereof is employed; said shaft having means for turning it and setting it in its adjusted positions as will be hereinafter described and claimed.

20 The object I accomplish by the construction shown in the accompanying drawing in which:

Figure 1 is a rear elevation of my improved signal in position on a wind shield 25 frame.

Fig. 2 is a detail sectional view of the rear end of the signal.

Fig. 3 is an elevation of the guide or bearing sleeve removed from the attaching 30 clamp.

Fig. 4 is a sectional side elevation of the signal.

Fig. 5 is a detail section on line 5—5, Fig. 3.

35 Fig. 6 shows a modified form of the attaching means.

An outwardly extending clamp 1, is formed of two jaws 2, 2, flanged vertically at their inner ends to grasp the vertical bar 40 3, of a wind shield frame and 4 is a clamping bolt to firmly secure the clamp in place. The outer ends of the jaws 2, 2, are given a twist as at 5—5 and the inner faces of these twisted or inclined portions are provided with sockets 6—6, receiving a spherical bearing 7, formed on the exterior of a tubular bearing 8. A bolt 9, extending through 45 the jaws serves to clamp the tubular bearing 8 in any adjusted position.

50 A rotary-reciprocating shaft 10, is mounted in the bearing 8 and has its outer end 11 bent laterally at an angle of about 45° and (to this end 11, and extending in the direction thereof is secured the base of 55 a combined signal lamp and pointer 12.

This lamp and pointer 12 constitutes the direction indicator by night as well as by day and also serves as a parking lamp in one of its adjusted positions. It comprises a triangular base 13 on the end 60 of the shaft 10, a triangular hollow globe 14 tapered from its base to its outer end or apex and provided along the edges of its larger inner end with flanges 15 which bear against the base 13 and to which they are 65 secured by a triangular grooved clamping band 16 the free ends of which are secured together by any suitable means, that shown being a bolt 17. By tightening this bolt the clamping band 16 will firmly bind the 70 flanges 15 to the base 13. The shaft 12 is preferably hollow to receive an electric wire 18 connected to a lamp socket 19 on base 13 said socket carrying an electric bulb 20.

The wire 18 enters the shaft through an 75 aperture 22, at its lower end and at this point the shaft has a dog 23, to engage any one of a series of four notches 24 formed on the lower end of the tubular bearing 8. This dog 23 is formed on the inner end of a sleeve 80 25 removably secured to the inner end of shaft 12 by a bolt 26; the sleeve 25 being further provided with an eye 27. The dog 23 is held in slip engagement with the notches 24 by means of a spring 28 encircling the shaft at the outer end of the bearing 8 and bears against said end and a collar 29 on the shaft 12. The shaft 12 is rotated by means of an operating rod 30 mounted in a bearing 33 carried by a collar 90 34 clamped to the steering post 37 just below the steering wheel of the machine. The rod 30 has an eye 31 engaging the eye 27 on shaft 12 and forming a universal joint therewith. The other end of the operating 95 rod 30 has a hand wheel 32 for rotating it. By means of the clamp 1 and the ball and socket connection of the tubular bearing 8 the shaft 10 may be properly set at the desired angle and position for various makes 100 of automobiles. When so positioned the shaft 10 extends outwardly, forwardly and upwardly but not beyond the outer margin of the side of the left fender. By this means sufficient space is left beyond the body of 105 the machine to bring the pointer 12 when swung to the right or left or upwardly, in view of machines approaching from the rear and the shaft 10 extends far enough in advance of the windshield and above the en-

110

gine hood to bring the pointer in full view of machines approaching at right angles. The electric conductor for the lamp may be supplied from a suitable battery or source not shown. The pointer or indicator 12, as before stated, is in the form of an elongated tapered globe, the three sides of which are of transparent material. One side is red and the two remaining sides are blue in color.

10 When the machine is running a straight course the pointer 12 will extend straight ahead in a horizontal line so the base thereof only, will be visible to following machines, while the two converging blue sides will

15 show to the left and the red side will show to the right. If the operator slows down or stops he will rotate the shaft 10 to the left until the pointer stands in a vertical position with its red side to the rear and the converging blue sides face forward. At night this

20 will serve as a parking light and so save that additional light. In turning to the left, the operator will turn the shaft 10 further to the left which will cause the pointer to stand out horizontally and point to the left with one of its blue sides facing rearwardly and one forwardly and the red side down. In

25 turning the machine to the right the shaft 10 will be turned one notch to the left from the straight ahead position and this will throw the pointer upwardly to the right where it will occupy an inclined position with its red side to the rear in view of following machines and its two converging blue sides visible to machine approaching from the right and left.

30 Thus a single rotatable inclined shaft is provided at its upper end with an illuminated triangular pointer projecting at an angle thereto and having its three sides contrastingly colored effectively serves all of the purposes desired in the direction and parking signals of automobiles. Various changes may be made within the scope of my invention.

35 In Fig. 6 is shown how the shaft 10 and its bearing sleeve 8 may be mounted in an opening 40 in the front 41 of a closed machine. The plates 1^a correspond to the plates 1 of Fig. 1, and 4^a are bolts securing the plates to the front 41.

What I claim is:

1. An automobile direction signal comprising an inclined operating shaft, and a triangular pointer secured at its rear end to the outer end of the shaft at obtuse angle thereto; said pointer normally pointing horizontally straight ahead, and means for turning the shaft to bring the pointer into its several indicating positions.

2. An automobile direction signal comprising an attaching means provided with an inclined guide, an inclined rotary shaft carried by said guide and provided at its outer end with a pointer projecting at an obtuse

angle thereto normally straight ahead, and means for rotating the shaft to bring the pointer into its indicating positions.

3. An automobile direction signal comprising an attaching means provided with an inclined guide, an inclined rotary shaft carried by said guide and provided at its outer end with a pointer projecting at an obtuse angle thereto and normally straight ahead, means for rotating the shaft, and means for yieldingly holding the shaft in any of its adjusted positions.

4. An automobile direction signal comprising an inclined rotary shaft, a bearing or support therefor, a hollow triangular pointer secured at its base to the outer end of the shaft and projecting at an obtuse angle horizontally forward therefrom; said triangle tapering from its rear end or base toward its front end or apex, and means for rotating the shaft.

5. In an automobile direction signal, a hollow, forwardly tapered, triangular pointer having transparent colored sides and open at its rear larger end, a forwardly and outwardly inclined operating shaft having its outer end projecting at an obtuse angle and provided with a base, a lamp socket carried by the base, means for securing the open rear end of the pointer to said base, and means for rotating the shaft to bring the pointer into its several indicating positions.

6. An automobile direction signal comprising a clamp adapted to be secured to the side bar of a wind shield frame and provided at its outer end with an outwardly, upwardly and forwardly inclined tubular bearing, a shaft rotatable in said bearing and having its outer end inclined at an obtuse angle, a hollow triangular pointer secured at its rear end or base to the said inclined end of the shaft, the sides of the pointer being transparent and in colors, and means for rotating the shaft to bring the pointer into its several indicating positions.

7. An automobile direction signal comprising a clamp to grasp the side rail of a wind shield frame, a tubular bearing, a ball and socket connection between the outer end of said clamp and the bearing to hold the sleeve at an outward, upward and forward inclination, a shaft mounted in said inclined bearing and having its outer end inclined at an obtuse angle, a direction signal or pointer secured to said bent end and projecting in the same direction therewith, and a yielding locking connection between the inner end of the shaft and the inclined bearing.

8. An automobile direction signal comprising a clamp for engagement with a wind shield frame, a tubular inclined bearing mounted on the outer end of the clamp, a rotary shaft extending through said bear-

- ing upwardly, outwardly and forwardly and having its outer end inclined at an obtuse angle, a pointer mounted on the outer inclined end of the shaft and projecting in the same direction therewith, a rotary operating rod operatively connected with the inner end of said shaft, and a bearing for the rod having means for connecting it with a steering post.
- 10 9. An automobile direction signal comprising an attaching clamp formed of two members adapted to grasp the side of a windshield frame, said members being twisted axially at their outer ends and provided on 15 their inner faces with socket portions, a tubular bearing having a ball forming member between its ends seated adjustably in said socket portions, a rotary shaft mounted in said tubular bearing and having a pointer
- projecting at an obtuse angle from its outer 20 upper end.
10. In an automobile direction signal, a hollow pointer triangular in form and tapered from its rear end forwardly; the sides of the pointer being colored and transparent, and an electric light socket within the pointer.
11. In an automobile direction signal, a rotary inclined shaft having its outer end set at an obtuse angle, a triangular socket- 30 carrying base plate on the end of said outer end, a triangular transparent pointer having a flanged rear end registering with the triangular base plate, and a clamping band engaging the marginal edges of the base 35 plate and pointer flanges.

In testimony whereof I affix my signature.
CLARENCE F. LYNN.
